TOY ANIMAL FIGURE

Morris C. Levich, New York, N. Y.

Application January 5, 1949, Serial No. 74

Term of patent 7 years

(Cl. D34—2)

To all whom it may concern:

Be it known that I, Morris C. Levich, a citizen of the United States, residing in the Borough of Manhattan, city, county, and State of New York, have invented a new, original, and ornamental Design for a Toy Animal Figure, of which the following is a specification, reference being had to the accompanying drawing, forming part thereof.

On the drawing,

Fig. 1 is a side view of a toy animal figure, showing my new design;

Fig. 2 is a front view of the toy animal figure illustrated in Fig. 1;

Fig. 3 is a rear view of the toy animal figure shown in Fig. 1;

Fig. 4 is a plan view of the toy animal figure shown in Fig. 1; and

Fig. 5 is a bottom plan view of the toy animal figure shown in Fig. 1.

The dominant features of my design are shown in full lines.

I claim:

The ornamental design for a toy animal figure, substantially as shown and described.

MORRIS C. LEVICH.
